Irvington, N. J.

Application March 26, 1954, Serial No. 29,699

Term of patent 14 years

(Cl. D44—5)

To all whom it may concern:

Be it known that I, Irvin Jack Gershen, a citizen of the United States, residing in the township of Hillside, county of Union, and State of New Jersey, have invented a new, original, and ornamental Design for a Refrigerated Butter Dish or Similar Article, of which the following is a specification, reference being had to the accompanying drawing, forming a part hereof.

Figure 1 is a side elevational view of a refrigerated butter dish or similar article, showing my new design;

and

I claim:

The ornamental design for a refrigerated butter dish or similar article, as shown.
